UNITED STATES PATENT OFFICE.

CHARLES R. PEIRCE, OF PHILADELPHIA, PENNSYLVANIA, ASSIGNOR TO
GEORGE J. NAYLOR, OF SAME PLACE.

IMPROVEMENT IN VEGETABLE GRATERS.

Specification forming part of Letters Patent No. 117,924, dated August 8, 1871.

To all whom it may concern:

Be it known that I, CHARLES R. PEIRCE, of the city of Philadelphia, in the State of Pennsylvania, have invented certain Improvements in Graters, of which the following is a specification:

My invention relates to the graters used for grating vegetables, crackers, &c.; and consists of a flat sheet-metal plate and a wooden frame or platform, constructed, arranged, and combined together, substantially as hereinafter shown and described; the object of my invention being to afford a more effective and durable grater, and at a less cost than those of equal size made of sheet metal entirely, as heretofore.

Figure 1 is a plan view of the upper or grating-side of the said improved grater. Fig. 2 is a vertical longitudinal section of Fig. 1. Fig. 3 is a vertical transverse section cut on the dotted line *x y* of Fig. 1.

The grating-plate A consists of a flat sheet of tin-plate about four and three-quarters of an inch by six and three-quarters, more or less, perforated from one side so as to produce a numerous series of quadrangular holes, *a' a'*, in diagonal lines crossing each other, each hole being about an eighth of an inch square, and forming on the opposite side four curved or angular elevated grating or cutting-edges inclined toward each other, as represented in the drawings. The frame consists of two wooden platforms, B B, each about three by four or five inches square and three-

eighths of an inch thick, more or less, connected together by two wooden side pieces, *b' b'*, each about twelve inches long, one inch wide, and three-eighths of an inch thick, more or less, which are nailed to the two respective edges of the platforms B B so as to leave an open space, *b''*, of rectangular form, between them, and so also that the two side pieces *b' b'* will form respective side guides or curves about half an inch high, more or less, along the upper side of the frame. These side pieces have each a groove, *3 3*, (see Fig. 3,) cut along in their inner sides so as to receive in the said grooves the side edges, respectively, of the plate A, which has its two ends, *2 2*, nailed down to the respective platforms B B, as shown in Figs. 1 and 2.

It will be readily understood, without further description, that the comparatively extensive and flat grating-surface formed by the tin-plate A and its application to the wooden platform B B and side guides *b' b'*, as described, will afford a more effective and durable grater, and at less cost than those made entirely of sheet metal and of the same size.

I claim as my invention—

As an article of manufacture, the vegetable grater hereinbefore set forth and described.

CHARLES R. PEIRCE.
